UNITED STATES PATENT OFFICE.

FREDERICK A. LIPPERT, OF CHICAGO, ILLINOIS, ASSIGNOR TO WENBORNE-KARPEN DRYER CO., OF CHICAGO, ILLINOIS, A CORPORATION OF WEST VIRGINIA.

DRYING-ROOM.

1,183,889.

Specification of Letters Patent. Patented May 23, 1916.

Application filed November 17, 1915. Serial No. 61,881.

To all whom it may concern:

Be it known that I, FREDERICK A. LIPPERT, a citizen of the United States of America, and a resident of Chicago, county of Cook, and State of Illinois, have invented certain new and useful Improvements in Drying-Rooms, of which the following is a specification.

This invention relates to drying rooms and particularly to the type which is used for drying coatings of varnish, paint, etc., on articles of manufacture such as automobiles, or furniture, and exemplified by U. S. Patents No. 918,621, issued April 20, 1909, to C. A. Wenborne; and No. 1,055,359, issued March 11, 1913, to E. A. Rummel; and Nos. 1,110,787 and 1,110,788, issued September 15, 1914, to Charles Hultgren. Devices of this class, besides being useful for general drying purposes, are intended particularly for drying or solidifying coatings of varnishes, etc., both by oxidation of such coatings, and by evaporation of volatile ingredients. These drying rooms usually operate by causing warm air to circulate around the objects being dried, through the action of suitably arranged heating and cooling devices.

The main objects of the invention are to provide improvements in the construction of drying rooms, and especially that class of drying rooms wherein circulation of the air is effected by natural draft; to provide a device of this class with improved means for moistening and washing the air which enters the room; to provide improved means for effecting the uniform circulation of air in the drying chamber and which permits of a definite control of the rate of discharge and renewal of the air; to provide an improved arrangement of fresh air inlet means; to provide an improved arrangement of the air cooling apparatus in such drying rooms; and in general to assemble and coördinate said improvements so as to provide a refined construction which insures a high degree of efficiency of operation, a practically uniform circulation of air throughout all parts of the drying chamber for effecting a uniform drying of articles therein, the recirculation of the air to a proper extent to avoid unnecessary loss of heat, the renewal of the air at a proper rate to avoid accumulation of fumes which might interfere with the drying action, and the

maintenance of a proper degree of humidity in the drying chamber to effect the rapid solidification of varnish without forming a skin on the outer surface of a varnish coating in advance of the hardening of the entire coating.

An illustrative embodiment of this invention is shown in the accompanying drawings, in which:

Figure 1 shows the improved drying room in perspective and partly broken away. Fig. 2 is a transverse section of the same. Fig. 3 is a longitudinal sectional view of the air washing and moistening device. Fig. 4 is a section on the line A—A of Fig. 3. Fig. 5 is a fragmentary, transverse section of the drying room, showing a modified arrangement of the outlet flue.

The drawings show a kiln having outer side walls 1, a ceiling or roof 2, and end walls 3, the latter being provided with doors so that articles may be passed progressively through the drying chamber or be put in and taken out at either end. An air moistening and washing device 4 may be placed at each corner of the kiln, as indicated in the drawing. Each one of these devices supplies air to an updraft inlet duct 5 which terminates in a distributing conduit 6 which extends from one end of the end walls of the kiln to a middle point along the upper edge of the side walls 1 and which is preferably of triangular cross section as shown, since in this form it occupies a space which is otherwise useless or detrimental and its inner face serves as a properly located deflector for the air rising from the heating flue or chamber. The conduits 6 have a plurality of outlets 7 which are located at successively different heights from the floor of the kiln. The lowest outlet 7 in the conduit 6 is located at the greatest distance from the inlet duct 5 and the highest outlet 7 being nearest the duct 5. By this arrangement of outlets 7, advantage is taken of the fact that the air entering the conduit 6 is comparatively cool and tends to spread out along the bottom thereof whereby some of the air flows past the nearby outlets 7 to the distant ones and all of the outlets discharge substantially equal quantities of air.

In about the same horizontal plane as outlets 7 are a plurality of air cooling devices 8 which cause the air entering the drying chamber to fall. Heating coils 9 are located

between the side walls 1 and partitions 10 spaced from the side walls to form narrow heating chambers or flues. These preferably extend substantially from end to end 5 of the drying chamber and have their bottom edges spaced away from the floor of the kiln and their upper edges spaced away from the roof 2 in order to permit the air to flow in at the bottom and out at the top 10 of the heating chambers.

The cooling devices 8 consist of a plurality of sections or coils of pipe through which water may circulate independently in each section from the header or manifold 11 and to the headers 12. The several coil units are connected to the manifolds by unions 13 which permit any coil to be removed at will without disconnecting the entire system. Water is supplied to the 15 header 11 through the feed pipe 14 and is discharged from the headers 12 through the discharge pipes 15 leading to the air moistening and washing devices 4.

The air moistening devices 4 comprise a 20 casing 16 having a screened opening 17 for the entrance of air. The pipes 15 entering the washing devices terminate in downwardly directed nozzles 18, each of which operates with a conical deflector 19 to form 25 an umbrella shaped spray through which the air entering the inlet 17 must pass before entering the vertical conduit 5. The air thus becomes moistened and washed before entering the kiln. Solid matter carried 30 by the air is carried out of the washing device with the water, which leaves the same through the pipe 20. The heaters 9 receive steam from the supply pipe 21, the supply being regulated by a pressure regulating 35 valve 22, as well as by the usual hand valve 40 not shown.

In order to provide a substantially uniform heating effect throughout the length of the heating chamber, inlet and outlet 45 manifolds are placed one above the other at one end and connected by a series of concentrically arranged U-shaped coils, each coil having its legs connected respectively to the inlet and outlet manifolds.

To bring about a continual inflow of fresh 50 air and outflow of used air, a plurality of air discharging flues 23 are provided. These extend upwardly through the heating chambers and have their inlet ends 24 suitably 55 spaced apart along the floor of the kiln to insure that the air is withdrawn uniformly from various parts of the kiln. The heaters are hung against the walls of the outlet flues 23, thus heating the air within and accelerating the draft. The flues 23 may be 60 bent inwardly along the inner inclined faces of the distributing ducts 6, and may then extend upwardly through the roof of the kiln and if desired may be connected together into a single duct, as indicated by

dotted lines at 25 at the left of Fig. 1. This construction is particularly desirable where the installation is made on the inside of a building, and it is desired to conduct the spent air and fumes upwardly to the roof 70 of the building. Or the outlet ducts 23 may discharge directly through the side wall of the kiln, as is illustrated in Fig. 5. Either of these constructions is suitable. The doors 26 for entrance and egress are placed in one 75 or both ends of the kiln.

Drip pans 27 are arranged under the cooling coils for collecting liquids condensed thereon and preventing the possibility of such liquids dripping upon the goods below, 80 and the cooling coils are preferably made up of units each consisting of a plurality of pipes placed one above the other in the same vertical plane, so that a single drip pan may serve for the entire unit.

The operation of the device shown is as follows: In drying articles coated with paint or varnish the drying room is first brought to the desired temperature by admitting steam to the heating coils and admitting 90 water to the cooling coils, and as soon as the desired temperature is reached the doors are opened and the trucks carrying the goods are put into the drying room. Regulation of the temperatures of the heating and cooling coils may be controlled automatically or by hand as described in the patents hereinbefore mentioned. During the normal operation of the device the air in the heating chambers is heated by means of the heating 95 coils 9 and caused to rise, new air flowing in from the drying room below the partitions 12 to replace the air as it rises. The rising air is then deflected inward by the inclined inner faces of the distributing ducts 100 6, and on account of being warmer than the air in the drying chamber spreads out along the ceiling thereof, and then becoming cooled through contact with the cooling coils 8 falls through the drying chamber and again flows upwardly through the heating chambers at each side of the drying chamber. A portion of the air flowing toward each side at the bottom of the drying chamber enters the outlet flues 23, and is carried away thereby.

The heating coils being in contact with the outlet flues give additional heat thereto, and increase the chimney effect thereof. New air, to take the place of the spent air conducted away by the ducts 23, enters the inlets 17 of the air washers 4, and after passing through the spray, by means of which it is cleaned and moistened, rises in the inlet ducts 5 and spreads out in the ducts 6 being delivered to the drying chamber throughout the length of the distributing ducts 6 by means of the outlets 7. The incoming air being cool, the air rising from the heating chambers mixes with the heated air and, therefore, coacts with the cooling coils in 115 120 125 130 135 140

chilling the heated air to cause it to fall through the drying chamber.

It will be readily understood that the areas of the fresh air inlets and the spent air outlets may be so proportioned as to continuously supply the proper amount of fresh air to properly condition the air in the drying room, or where circumstances require they may be provided with means for varying the flow of air therethrough, as in the hereinbefore mentioned patents. It is, of course, desirable to recirculate the air as much as is consistent with efficient drying conditions, so as to avoid unnecessary waste of heat through the discharge of spent air. The amount of replenishment of the air which may be desirable is largely dependent upon the nature of the coatings which are being dried. Those which contain a large amount of volatile matter tend to contaminate the air more rapidly than those which consist mainly of ingredients which dry by oxidation.

If the kiln is installed in the interior of a building so that its air inlets and outlets communicate with the air within the building, then the operation of the device is practically independent of changes in weather conditions. On the other hand if the location of the installation is such as to be to some extent influenced by weather conditions, then variations in such conditions may be easily offset by variation in the flow of water in the cooling coils, as is well known.

Although but one specific embodiment of this invention has been herein shown and described, it will be understood that numerous details of the construction shown may be altered or omitted without departing from the spirit of this invention as defined by the following claims.

I claim:

1. A kiln, comprising a drying chamber, a heating chamber at one side of same and communicating therewith at the top and bottom, an air inlet duct extending along said drying chamber above said heating chamber and having a series of openings distributed along its length for supplying fresh air to said drying chamber, a wall of said duct being shaped to deflect the air from said heating chamber toward said drying chamber whereby the same will mix with the air from said openings, and an outlet flue communicating with said drying chamber near the bottom.

2. A kiln, comprising a drying chamber, a heating chamber at one side of same and communicating therewith at the top and bottom, an air inlet duct extending along said drying chamber above said heating chamber and having a series of openings distributed along its length for supplying fresh air to said drying chamber, a wall of said duct being shaped to deflect the air from said

heating chamber toward said drying chamber whereby the same will mix with the air from said openings, cooling means above said drying chamber and in the path of the heated air, and an outlet flue communicating with said drying chamber near the bottom. 70

3. A kiln, comprising surrounding walls and a roof, a partition spaced inwardly from one of said walls and providing communication between the interior of the kiln and the space between said wall and partition at its upper and lower ends, and an air inlet conduit arranged above said partition in the corner formed by said wall and roof and having an inclined face for the purpose of deflecting air which travels upwardly between said wall and partition toward the center of the kiln, said conduit having a plurality of openings distributed along its 80 inclined face. 85

4. A kiln, comprising surrounding walls and a roof, a partition spaced inwardly from one of said walls and providing communication between the interior of the kiln and the space between said wall and partition at its upper and lower ends, and an air conduit arranged above said partition in the corner formed by said wall and roof and having an inclined face for the purpose 95 of deflecting air which travels upwardly between said wall and partition toward the center of the kiln, said air conduit having a plurality of openings in said inclined face arranged along the length of said conduit 100 but in different horizontal planes. 100

5. A kiln, comprising surrounding walls having an air inlet and deflectors at their upper edges for directing upward currents of air toward the center of the kiln, partitions spaced inwardly from said walls, said partitions having openings near their top and bottom, heating means between said partitions and walls, and a plurality of spaced and vertically arranged outlet flues 110 between said partitions and walls, said outlet flues being bent to follow the contour of said walls and deflectors. 105

6. A kiln, comprising surrounding walls and a roof, a partition spaced inwardly 115 from one of said walls and providing communication between the interior of the kiln and the space between said wall and partition at its upper and lower ends, and an air inlet conduit arranged above said partition in the corner formed by said wall and roof and having an inclined face for the purpose of deflecting air which travels upwardly between said wall and partition toward the center of the kiln, said inlet conduit having a fresh air inlet and having in its inclined face a series of air outlets located at different levels, being successively lower as their distance from said inlet increases. 120 125 130

7. A kiln, comprising a drying chamber, a heating chamber at one side of same and communicating therewith at the top and bottom, an air inlet duct extending along 5 said drying chamber above said heating chamber and having a series of openings distributed along its length for supplying fresh air to said drying chamber, a wall of said duct being shaped to deflect the air 10 from said heating chamber toward said drying chamber whereby the same will mix with the air from said openings, a fresh air inlet communicating with said inlet conduit, and an air washer in the path of the 15 inflowing air.
8. A kiln, comprising a drying chamber, a heating chamber at one side of same and communicating therewith at the top and bottom, an air inlet duct extending along 20 said drying chamber above said heating chamber and having a series of openings distributed along its length for supplying fresh air to said drying chamber, a wall of said duct being shaped to deflect the air 25 from said heating chamber toward said drying chamber whereby the same will mix with the air from said openings, cooling coils above said drying chamber and in the path of the heated air, a fresh air inlet flue 30 communicating with said inlet conduit, and an air washer in the path of the inflowing air, said washer having water spraying means connected to the outlet end of said cooling coils.
- 35 9. A dry kiln, comprising a drying chamber, a heating chamber at one side thereof and communicating therewith at the top and bottom, heating means in said heating chamber, separate air inlets for the 40 two ends of said heating chamber, individual distributing ducts communicating with said air inlets and respectively ex-
- tending along the opposite end portions of 45 said heating chamber above said heating means and having outlets at intervals along the length thereof, and outlet flues communicating with said drying chamber near the bottom thereof and extending upwardly through said heating chamber.
10. A dry kiln, comprising a drying 50 chamber, heating chambers at opposite sides thereof and communicating therewith at the top and bottom, heating means in 55 said heating chambers, separate air inlets for the two ends of each of said heating chambers, individual distributing ducts communicating with said air inlets and respectively extending along the opposite end portions of 60 said heating chambers above said heating means and having outlets at intervals along the length thereof, and outlet flues communicating with said drying chamber near the bottom thereof and extending upwardly through said heating chambers.
- 65 11. A dry kiln, comprising a drying chamber, a heating chamber at one side thereof and communicating therewith at the top and bottom, heating means in 70 said heating chamber, separate air inlets for the two ends of said heating chamber, individual distributing ducts communicating with said air inlets and respectively extending along the opposite end portions of 75 said heating chamber above said heating means and having outlets at intervals along the length thereof, outlet flues communicating with said drying chamber near the bottom thereof and extending upwardly through said heating chamber, and air 80 washers in said air inlets.

Signed at Chicago, this 2nd day of Nov.
1915.

FREDERICK A. LIPPERT.
